16 John Robert Kelley Inventor
By C. W. Miles.

By C. W. Miles.

Attorney.

UNITED STATES PATENT OFFICE.

JOHN ROBERT KELLEY, OF COVINGTON, KENTUCKY.

RADIOGRAPHIC APPARATUS.

Application filed August 22, 1925. Serial No. 51,852.

My invention relates to improvements in radiographic apparatus. One of its objects is to provide improved means to support and shield X-ray tubes. Another object is to provide improved apparatus to support and give ready access to the X-ray tube. Another object is to provide improved means to support and shield X-ray tubes, and to provide for readily inserting, removing, substituting or replacing the tubes. Another object is to provide improved adjustable means to adjustably center, support, and shield X-ray tubes, even where respective tubes are relatively different in dimensions. 15 My invention also comprises certain details of form and combination of components, all of which will be fully set forth in the description of the accompanying drawings, in which:

20 Fig. 1 is a plan of my improved apparatus. Fig. 2 is a side elevation of the same. Fig. 3 is a vertical section through the same taken on line 3—3 of Fig. 2. Fig. 4 is an end view of Figs. 1 and 2. 25 Fig. 5 is a sectional detail taken on line 5—5 of Fig. 1.

The accompanying drawings illustrate the preferred embodiment of my invention in which 15 represents a supporting plate preferably of metal, having an opening or window 16 through which the X-rays are designed to pass from an X-ray tube 17 through the subject to be radiographed and thence to a sensitive photographic plate, not shown. It 30 is designed to place the patient or subject to be radiographed upon a table, to support the sensitive plate within a plate holder slipped into a recess in the table beneath the patient, and to support the plate 15 and members carried thereby adjustably above the patient by means of an adjustable overhanging arm or bracket to which the plate 15 is detachably attached. X-ray tubes differ considerably in dimensions, one from another, and also in their qualities and adaptability to the different types of work in hand. They are also fragile and liable to injury. It frequently happens that one tube requires to be removed and another substituted, which it is desirable to accomplish conveniently and quickly. It is also desirable to shield the operator, his assistants, and his sensitive plates, and other apparatus, and also the patient except at the locality to 35 50 55 be radiographed from the influence of X-

rays issuing from the X-ray tube 16 when energized.

These various features of adjustment support, and shielding are accomplished with my improved apparatus in the following 60 manner.

A shield preferably of lead-glass, and impervious to X-rays is composed of two sections 20 and 21, which are separable along a substantially horizontal line. The lower section 20 is detachably clamped to the plate 15 by means of an outwardly extending annular flange 22, which is engaged by a series of clamping members 23, held in place by bolts 24. The shape of the section 20 is that 70 of the lower half of a hollow spherical body having semi-tubular horizontal ends 25 and 26 and an annular wall 27 extending downwardly to the flange 22 and providing an opening 28 leading down from the interior 75 of the spherical shield to the window 16 in the plate 15. The shield section 21 comprises the upper half of a hollow spherical body having a projection 29 and semi-tubular horizontal ends 30 and 31 which are 80 counterparts to the sections 25 and 26 of the lower shield member 20. The semi-tubular ends 25, 26, 30 and 31 are each provided with a semi-annular groove 32 which grooves are respectively engaged by counterpart ribs 85 34 carried by the upper embracing members 35 and 36 and the lower embracing members 37 and 38. The members 35 and 37 are connected together by a hinge member 39 and are detachably clamped together at their opposite edges by means of an eye-bolt 40 and a clamping nut 41. The eye-bolt 40 is connected by a pin 42 to the embracing member 37 and enters a slot 43 in the edge of member 35. By loosening the nut 41, the eye-bolt 40 turns on the pin 42 and leaves the slot 43, to quickly free the member 35 and allow member 35 to be thrown upwardly and backwardly upon its hinge 39 out of engagement with shield section 21. The embracing members 36 and 38 are hinged together by a hinge member 45, similar to the hinge member 39, and at their opposite edges are detachably connected together by an eye-bolt 46 and clamping nut 47 similar to the 90 eye-bolt 40 and clamping nut 41, and operable as described for the eye-bolt 40 and nut 41 to allow the member 36 to be turned upwardly and backwardly upon its hinge 45. The members 37 and 38 are preferably 100 105 110

clamped rigidly to the plate 15 by means of bolts 48 and nuts 49, but may if desired be rigidly or detachably clamped to the lower shield member 20, instead of to the plate 15.

5 The X-ray tube 17 comprises an intermediate substantially spherical section 50 with cylindrical projections or sections 51 and 52 at opposite sides thereof to the ends of which are attached electrical terminals 53 and 54. In order to adjustably and detachably support the X-ray tube within and relative to the shield members 20 and 21, I provide projections 55 extending outwardly from the lower embracing members 37 and 38 which projections are perforated to receive the cylindrical or polygonal posts or shanks 56 held adjustably in place by means of set screws 57. At the upper ends of the posts 56 are curved supporting shoes 58 each provided with a soft lining 59 of cork, wool-felt, or similar material upon which the cylindrical sections 51 and 52 of the X-ray tube rest, and thereby support the tube 17 out of contact with the lower shield member 20, and enable the tube 17 to be adjusted concentrically with the openings in the shield through which the cylindrical tube sections 51 and 52 project.

25 The embracing members 35 and 36 are each provided with a projection 60 similar to the projections 55 which are bored to receive the cylindrical or polygonal stems 61, to the lower ends of which are attached curved shoes 62 each being provided with a soft lining of cork, wool-felt, or similar material 35 63. The stems 61 are adjustable in the projections 60, and are clamped rigidly to their adjusted positions by set screws 64. The shoes 62 and their lining members 63 engage 40 the top of the cylindrical sections 51 and 52 of the X-ray tube to co-act with the shoes 58 in clamping the X-ray tube lightly but rigidly in its position within and relative to the shield members 20 and 21, and provide 45 for adjusting the X-ray tubes to a position concentric with and out of contact with both shield members 20 and 21. The tube is also supported in such manner that expansion and contraction of the tube may take place 50 without injury to the tube. Also the upper section of the shield 21 including the embracing members 35 and 36 carrying with them the shoes 62, may be readily released and removed, thereby giving access to the 55 tube resting loosely upon the linings 59 of the shoes 58, and permitting the tubes to be removed and replaced if desired. The members 35 and 36 both open from the front and thus contribute to convenient access to 60 the tubes. The spherical section of each tube is provided with a projection 66 which serves to seal the tube after the tube has been exhausted. The projection 29 in the wall of the shield member 21 provided for 65 assembling the tubes and shield, with the

projection 66 of the tube extending into one end or the other of the recess formed by the projection 29, depending upon whether the tube is inserted with the projection 66 to the right hand or to the left hand. The meeting edges 67 and 68 of the shield members 20 and 21 are off-set so as to facilitate the assembly of the members 20 and 21 in alignment with each other, and also to avoid any possible leakage of X-rays through the joint 70 between the members 20 and 21. The recesses 32 and counterpart ribs 34 serve to hold the shield members 20 and 21 in alignment endwise, and to prevent relative displacement of either the shield members 20 80 and 21 or displacement of the embracing members 35, 36, 37 and 38 relative to each other or to the shield members.

The apparatus herein shown and described is capable of considerable modification within the scope of the claims without departing 85 from the spirit of my invention.

What I claim is:

1. Radiographic apparatus comprising a hollow X-ray tube shield having openings at 90 opposite sides for the passage of opposite ends of the X-ray tube and divided along lines leading from one of said openings to the other to permit the shield to be separated into two sections to provide for introducing and removing the X-ray tubes, a port for the issuance of X-rays from the interior of said shield, supporting members carried rigidly relative to one of said shield sections upon which the X-ray tube normally 95 rests near opposite ends of said tube, clamping members adjustable to engage and clamp said tube in position upon its supporting members and serving also to clamp said shield sections together.

2. Radiographic apparatus comprising a hollow X-ray tube shield having openings at opposite sides for the passage of opposite ends of the X-ray tube and divided along 100 lines leading from one of said openings to the other to permit the shield to be separated into two sections to provide for introducing and removing the X-ray tubes, a port for the issuance of X-rays from the interior of said shield, supporting members carried 105 adjustably and rigidly relatively to one of said shield sections upon which the X-ray tube normally rests near opposite ends of said tube, main clamping members adjustable to engage and clamp said shield sections together, and auxiliary clamping members carried adjustably and rigidly by 110 said main clamping members to engage and clamp the X-ray tube upon its supporting members.

3. Radiographic apparatus comprising a hollow X-ray tube shield having openings at opposite sides for the passage of opposite ends of the X-ray tube, and divided along 115 lines leading from one of said openings to 120

- the other to permit the shield to be separated into an upper section and a lower section to provide for introducing and removing the X-ray tubes, a port for the issuance of X-rays from the interior of said shield, supporting members carried rigidly relative to the lower shield section upon which opposite ends of the X-ray tube normally rest to support the X-ray tube within its shield, main clamping members adjustable to detachably clamp the upper shield section upon said lower shield section, and auxiliary clamping members carried by and movable with said main clamping member to clamp said tube at opposite ends upon the tube supporting members at the same time that said shield sections are clamped together.
4. Radiographic apparatus comprising a hollow X-ray tube shield having openings at opposite sides for the passage of opposite ends of the X-ray tube, and divided along lines leading from one of said openings to the other to permit the shield to be separated into an upper section and a lower section to provide for introducing and removing the X-ray tubes, a port for the issuance of X-rays from the interior of said shield, supporting members adjustably mounted and carried rigidly relative to the lower shield section upon which opposite ends of the X-ray tube normally rest to support the X-ray tube substantially concentrically within its shield, main clamping members adjustable to detachably clamp the upper shield section upon said lower shield section and auxiliary clamping members adjustably mounted upon said main clamping members to engage and clamp the X-ray tube upon its supporting members.
5. Radiographic apparatus comprising a hollow X-ray tube shield having openings at opposite sides for the passage of opposite ends of the X-ray tube, and divided along lines leading from one of said openings to the other to permit the shield to be separated into an upper section and a lower section to provide for introducing and removing the X-ray tube, a port for the issuance of X-rays from the interior of said shield, resiliently faced supporting members carried rigidly relative to the lower section of said shield to normally engage opposite ends of the X-ray tube to support the X-ray tube within said shield, main clamping members to detachably clamp the upper shield section in position upon the lower shield section, and resiliently faced auxiliary clamping members carried by and movable with said main clamping members to clamp the X-ray tube from above in position upon said tube supporting members when said shield sections are clamped together.
6. Radiographic apparatus comprising a main tube and shield supporting member, a hollow X-ray tube shield having openings at opposite sides for the passage of opposite ends of the X-ray tube and divided along lines leading from one of said openings to the other to permit the shield to be separated into an upper section and a lower section to provide for introducing and removing the X-ray tubes, a port through the wall of said lower shield section and said main tube supporting member for the issuance of X-rays from said shield, means to clamp the lower shield section rigidly to said main tube support and clamping members at opposite sides of said shield adjacent to the side openings in said shield pivotally attached relative to said main tube support and movable into and out of position to detachably clamp and lock said upper shield section to said lower shield section and to enable the upper shield section to be detached from the lower shield section.
7. Radiographic apparatus comprising a main tube supporting member, a hollow X-ray tube shield having openings at opposite sides for the passage of opposite ends of the X-ray tube and divided along lines leading from one of said openings to the other to permit the shield to be separated into an upper section and a lower section to provide for introducing and removing the X-ray tubes, a port through the wall of said lower shield section and said main tube supporting member for the issuance of X-rays from said shield, an annular flange on said lower shield section clamped to said main tube supporting member, clamping members having projections interengaging with corresponding depressions in said shield to detachably clamp the shield sections together and to enable the upper shield section to be detached from the lower shield section to introduce and remove X-ray tubes.

In testimony whereof I have affixed my signature,

JOHN ROBERT KELLEY.
